UNITED STATES PATENT OFFICE.

JOHN CARMICHAEL, OF FRANKLIN, WASHINGTON.

MACHINE FOR CUTTING, EXPANDING, AND BEADING TUBES OR FLUES.

SPECIFICATION forming part of Letters Patent No. 717,344, dated December 30, 1902.

Application filed December 11, 1901. Serial No. 85,429. (No model.)

To all whom it may concern:

Be it known that I, JOHN CARMICHAEL, a citizen of the United States, and a resident of Franklin, in the county of King and State of Washington, have invented a new and Improved Machine for Cutting, Expanding, and Beading Tubes or Flues, of which the following is a full, clear, and exact description.

The object of the invention is to provide a new and improved tube cutting, expanding, and beading machine which is simple and durable in construction, readily applied and fastened in position on a boiler, and conveniently operated to permit of cutting a tube to the proper length for beading or to cut an old tube for removal from the boiler, to expand the flue for setting it firmly in the tube-sheet, and to bead the end of the tube to securely hold the same in position in the boiler.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement as applied. Fig. 2 is an enlarged transverse section of the same on the line 2 2 of Fig. 1. Fig. 3 is an enlarged sectional elevation of one of the expanding-rollers and its bearing. Fig. 4 is a side elevation of one of the flaring rollers and its bearing. Fig. 5 is an enlarged sectional side elevation of the beader as applied. Fig. 6 is an enlarged transverse section of the fastening device for the frame or support, the section being on the line 6 6 of Fig. 1; and Fig. 7 is an enlarged end elevation of the barrel-bearing.

The frame or support A of the machine is provided with a fastening device for securing the frame in an operative position on the front of a flue-sheet B, and this fastening device engages a flue B' or an opening in the flue-sheet while the expander, cutter, or beader is operating on another tube or flue B², as will be readily understood by reference to Fig. 1. The fastening device consists, essentially, of a plurality of blocks C, mounted to slide radially in bearings on a tubular extension A'

of the frame A, and the inner ends of the said blocks C engage a tapering mandrel C', connected at its outer or base end with a screw-rod C², screwing in a nut C³, held on the frame or support A, the outer end of the screw-rod being provided with a hand-wheel C⁴ to permit of conveniently turning the screw-rod to screw the same inward or outward in the nut C³, according to the direction in which the hand-wheel C⁴ is turned. When the screw-rod C² is screwed inwardly, the mandrel C' is moved inwardly and centrally in the flue B', so as to push the blocks C outward to cause the outer toothed ends thereof to move into firm contact with the inner surface of the flue B' to securely hold the extension A' and the frame A in position on the boiler. When it is desired to remove the device from the boiler, the screw-rod C² is caused to move outward to disengage the blocks C from the flue B' to permit the operator to remove the frame from the boiler.

In order to cut off, expand, or flange the flue B², I provide a barrel D, mounted to turn in a bearing E, having an inwardly-extending flange E', adapted to rest on the flue-sheet B, the barrel D being held against inward movement on the said bearing E by a collar D', arranged on the outer end of the barrel and abutting against the outer face of the bearing E, as plainly indicated in Fig. 1. The upper end of the bearing E is connected with a frame part A², pivoted at A³ on a vertical pivot to the main frame A to permit of swinging the frame part A² to one side whenever it is desired to do so. The pivoted part A² of the frame is provided with a hook A⁵ for engaging the bearing E, as shown. In the barrel D are formed longitudinal slots or bearings for tapering blocks F to slide radially in and out, (see Fig. 2,) and in each of the said blocks F is removably journaled a circular cutter G, adapted to engage the flue B² at the inside, so that when the barrel is turned and with it the blocks F and the latter are forced outwardly the cutters G cut the flue B². When it is desired to expand the flue, rollers G² are journaled in the blocks F, (see Fig. 3,) and when it is desired to flange the outer end of a tube B² flanging-rollers G² are journaled in the said blocks, as illustrated in Fig. 4, the flanging-rollers being in the shape of a frus-

tum of a cone having concave sides. The same blocks may be used for carrying the cutters and rollers; but I preferably employ a separate block for each. The journals of the cutters G and the rollers G' and G² are held in position in the blocks F by flat springs L, which permit yielding of the said cutters and rollers, and the blocks F are similarly pressed on their outer faces by springs L', secured to the peripheral surface of the barrel D. The inner sides of the several blocks F rest on the sides of a tapering mandrel H, polygonal in cross-section, as plainly shown in Fig. 2, so that when the mandrel is turned a rotary motion is given to the barrel D by the blocks F, turning with the mandrel H, and consequently the cutters G and rollers G' or G² travel transversely on the inside of the flue B². When the mandrel H is moved inwardly, the blocks F are pushed outwardly, so as to feed the cutters G and rollers G' and G² outwardly to properly cut, expand, or flange the flue B². In order to give the mandrel H the desired rotary motion for the purpose described, I provide a gear-wheel I, turning with the mandrel H and sliding on the outer cylindrical portion thereof, the said gear-wheel I being for the purpose provided with a suitable key engaging a corresponding keyway arranged longitudinally in the cylindrical outer portion of the mandrel H. The gear-wheel I is held against longitudinal movement by lugs A⁴ on the frame part A², and the said gear-wheel is in mesh with a gear-wheel J, secured on a shaft J', journaled in suitable bearings on the main frame A. On the outer end of the shaft J' is secured a crank-arm J², adapted to be turned by the operator to rotate the shaft J' and gear-wheel J, so that the latter imparts a rotary motion to the gear-wheel I, which in turn turns the mandrel H for the purpose above described. In order to feed the mandrel H inward, and thus move the blocks F outwardly, as before stated, I connect the outer end of the mandrel H by a pin K' with a screw-rod K, screwing in a nut A⁵, arranged on the frame part A². On the outer end of the screw-rod K is secured a hand-wheel K², under the control of the operator, for screwing the screw-rod K inward to move the mandrel H in the corresponding direction for forcing the blocks F outward, as above stated. Each block F is preferably formed with a number of bearings to permit of using the same cutters G for cutting off pipes or tubes within the boiler when the same are to be removed or cutting off the ends of the tubes that project beyond the tube-sheet preparatory to beading the same, it being understood that for cutting off tubes within the boiler the cutters are placed in the bearings at the inner ends of the blocks F and in the bearings at the outer ends of the blocks when the ends of the tubes are to be cut off. When it is desired to bead the projecting end of the flue B², the following arrangement is made, special reference being had to Fig.

5. The mandrel H', which is of uniform diameter, is connected with the screw-rod K by the pin K' and also carries a gear-wheel I. The inner end of the mandrel H' abuts against the flanges O' of blocks O, mounted in the slots or bearings of the barrel D and carrying at the forward end beading-rollers P and at the inner end guide-rollers Q. The beading-rollers P have their axes extending radially relative to the mandrel H', while the guide-rollers Q have their axes extending parallel with the axes of the barrel D and mandrel H'. It is understood that when the beader is used and the screw-rod K is screwed inwardly the mandrel H' pushes the blocks O in a like direction, so as to firmly engage the beading-rollers P with the outer end of the tube or flue to bead the same in the proper manner. By turning the crank-arm J² the mandrel H' is rotated, and with it the barrel D, to bring the beading-rollers in contact with the outer end of the flue. The collar D' holds the blocks O against outward movement in the barrel D.

From the foregoing it will be evident that the machine is very simple and durable in construction, and by the use of the fastening device described the machine can be readily secured in place to bring the cutter, expander, and beader in proper relation to the flue to be treated.

Having thus described my invention, I claim as new and desire to secure by Letters Patent—

1. A machine for cutting, expanding and beading tubes or flues, comprising a supporting-frame, a slotted barrel mounted to turn, sliding cutter or roller carrying blocks mounted in the slots of the barrel, a longitudinally-sliding mandrel for engaging the said blocks, a gear-wheel through which the mandrel slides, means for holding the gear-wheel from longitudinal movement, and a shaft mounted in the frame and provided at its outer end with means for operating it and at its inner end with a gear-wheel meshing with the first-named gear-wheel, as set forth.

2. A machine for cutting, expanding and beading tubes or flues, comprising a frame, means for securing the frame to a boiler, a bearing adapted to rest against a boiler, a slotted barrel mounted to turn in said bearing, sliding cutter or roller carrying blocks mounted in the slots of the barrel, a mandrel engaging the said blocks, means engaging the mandrel for moving it longitudinally, a gear-wheel through which the mandrel slides, means carried by the frame for holding the gear-wheel from longitudinal movement on the mandrel, and a shaft mounted in the frame, and provided at its outer end with means for turning it and at its inner end with a gear-wheel meshing with the gear-wheel on the mandrel, as set forth.

3. A machine for cutting, expanding and beading tubes or flues, comprising a frame having a pivoted member, means for secur-

- ing the frame to a boiler, a bearing adapted to engage a boiler and with which the pivoted member of the frame engages, a slotted barrel mounted in the bearing, sliding cutter or roller carrying blocks mounted to slide in the slots of the barrel, a mandrel engaging the said blocks, a gear-wheel through which the mandrel slides, lugs carried by the pivoted member of the frame and between which the gear-wheel extends, a screw mounted in the pivoted member of the frame and engaging the end of the mandrel, and a shaft mounted in the frame and provided at its outer end with a crank-handle and at its inner end with a gear-wheel meshing with the gear-wheel on the mandrel, as set forth. 35
4. A machine for cutting, expanding and beading tubes or flues, comprising a mandrel for rotating the cutting-tools and for feeding the same in contact with the tube or flue, a gear-wheel mounted to turn with the mandrel and slidably connected therewith, means for holding the gear-wheel against longitudinal movement on the mandrel, a manually-controlled shaft having a gear-wheel in mesh with the mandrel gear-wheel, and a screw-rod screwing in a fixed nut and engaging the said mandrel, as set forth. 40
5. In a machine for cutting, expanding and beading flues or tubes, a frame having a member pivoted to swing laterally and provided with spaced lugs, a bearing adapted to rest against a boiler and with which the free end 45
- of the pivoted member of the frame engages, a barrel carrying cutters or rollers and mounted in the bearing, a mandrel for forcing the cutters or rollers out of the barrel, a screw mounted in the pivoted member of the frame for moving the mandrel longitudinally, a gear-wheel through which the mandrel slides, said gear-wheel projecting between the lugs of the pivoted member of the frame, a gear-wheel mounted in the frame and meshing with the first-named gear-wheel, and means for operating the last-named gear-wheel, as set forth. 50
6. In a machine for cutting, expanding and beading flues or tubes, the combination with a slotted barrel mounted to turn, sliding cutter or roller carrying blocks mounted in the slots of the barrel, a sliding mandrel, and means for operating the mandrel, of a frame in which the mandrel and its operating means are mounted provided with a tubular slotted extension, blocks mounted in the extension and projecting through the slots of the same, a mandrel for forcing the blocks outward, a nut carried by the frame, and a screw-rod mounted in the nut and connected with the outer end of the mandrel, as set forth. 55
- In testimony whereof I have signed my name to this specification in the presence of two subscribing witnesses.
